UNITED STATES PATENT OFFICE.

WILLIAM S. FLATOW, OF BROOKLYN, NEW YORK.

GARMENT SEAM.

1,403,308.

Specification of Letters Patent. Patented Jan. 10, 1922.

Application filed February 17, 1920. Serial No. 359,368.

To all whom it may concern:

Be it known that I, WILLIAM S. FLATOW, a citizen of the United States, and a resident of the city of New York, borough of Brooklyn, in the county of Kings and State of New York, have invented a new and Improved Garment Seam, of which the following is a full, clear, and exact description.

The present invention relates to new and useful improvements in garments, and it pertains more particularly to seams therein.

The primary object of the present invention is to so construct a seam that the same may be readily ripped or separated to provide for the disassembly of the several parts which go to make up the garment.

A seam constructed in accordance with the present invention is especially adapted for use in connection with men's shirts, and the same is more particularly useful for attaching the cuffs to the sleeves, and the front members of the shirt to the sleeves, shoulder members and neckband. Owing to the character of collars commonly worn, shirts are subjected to wear at that portion where the front members of the shirt join the neckband, and it very often happens that with some styles of collars the shirt will be worn through at that portion before the remainder 30 of the garment shows any indication of wear.

It is a further object of the present invention to construct a shoulder seam and neckband seam of a shirt in such a manner that the front members thereof may be removed, recut and again positioned to present an unworn surface at the base of the collar band.

It is also desirable at times to reverse the cuffs of shirts, and it is a further object of the invention to use this seam for securing the cuffs to the sleeves in such a manner that the cuffs may be readily removed and resewn in the reverse position.

With the above and other objects in view, reference is had to the accompanying drawings in which—

Figure 1 is a front elevation of a shirt constructed in accordance with the present invention, and

Fig. 2 is a detail sectional view showing the same construction of the cuffs.

Referring more particularly to the drawings, the shirt comprises a back section 5, two front sections 6 and 7, and sleeve members

8. The sleeve members 8 are secured to their respective front sections by means of a seam 9, and said seam 9 extends upwardly and over the shoulder portion and serves to secure the front sections to the back section, as indicated by the reference character 10. The reference character 11 designates a collar-band, and said collar-band is secured to the front sections 6 and 7 by means of said seam 9, as indicated by the reference character 12. The collar band 11 is secured to the back section by means of a seam 11' in the usual manner.

Secured to each of the sleeve members 8, is a cuff 13, and each of said cuffs 13 is secured to its respective sleeve member by means of a seam 14, which in this instance is of the same construction as the seam 9.

By reference to Fig. 2, it will be seen that the seams 9 and 14 are constructed in the following manner:

In this figure, the reference character 8 designates one of the sleeve members, and 13 designates the cuffs, preferably of the double type. When the cuff is attached to the sleeve member 8, by the stitching 20, a tape 21 is likewise secured in the same line of stitching 20 in such a manner that the same is invisible when the seam is completed. As indicated by the reference character 25, however, a portion of each end of the tape is exposed in order that the same may be gripped for a purpose to be hereinafter set forth. By this construction, it will be seen that when the cuffs become worn, it is only necessary to exert a pull on the tape 21, which action rips the stitches of the seam 20 and causes a detachment of the cuffs 13.

As more clearly shown in Fig. 1, the tape is secured in that portion of the seam 9 indicated by the reference character 10 and extends around a portion of the collar-band 11 having its ends projected slightly beyond the edges of the seams as indicated by the reference character 21 and shown in Fig. 1.

Should the front portions 6 and 7 of the shirt become worn, it will only be necessary to grip the end of the tape 21 and exert a pull thereon, which action will sever the seams 10 and 12, and leave the upper ends 105 of the front members 6 and 7 detached from the neckband and back. After these seams have been severed, it is only necessary to re-cut the neck portions of the front members 6 and 7 and move the front members 110

upwardly. The recut portions may now be sewn to the several parts by a suitable line of stitching.

By this construction it will be apparent that the present invention provides a seam capable of being readily severed for the purpose of ripping up a garment into the several pieces from which it is formed, and, furthermore, that such an action is particularly adapted for garments wherein certain parts are subjected to excess wear and are therefore adapted to be removed for the purpose of renewal or different positioning.

Claim:

A shirt having permanently attached removable front sections, the front sections of said shirt being secured to the remainder of the shirt by means of a tape extending throughout the side seams of the shirt, a portion of the arm seams of the shirt, the shoulder seam, and a portion of the neckband, said tape terminating at the neckband closure and projecting slightly therefrom, said tape serving to open the seam upon exerting a strain thereon.

WILLIAM S. FLATOW.
